COAT HANGER

Bruce Bernstein, New York, N.Y., assignor to Handiform Plastic Corp., New York, N.Y.

Filed Jan. 3, 1975, Ser. No. 538,446

Term of patent 3½ years

Int. Cl. D6—08

U.S. Cl. D6—247

FIG. 1 is a front elevational view of a coat hanger showing my new design;

FIG. 2 is a bottom plan view thereof;

FIG. 3 is a side elevational view taken from the left of FIG. 1;

FIG. 4 is a side elevational view taken from the right of FIG. 1; and

FIG. 5 is a top plan view thereof.

I claim:

The ornamental design for a coat hanger, substantially as shown.
